METAL CONTAINER

Alfred L. Kronquest, Syracuse, N. Y., assignor to
 Continental Can Company, Inc., New York,
 N. Y., a corporation of New York

Application June 2, 1932, Serial No. 614,996

1. Claim. (Cl. 220—54)

The invention relates to new and useful improvements in metal containers which are made easy to open by a tearing strip and which have an inserted collar in the region of the tearing strip. In my application Serial No. 593,915, filed February 18, 1932, there is shown, described and claimed an easy opening container having an inserted collar which is held therein by the frictional grip of the central portion of the collar with the container body. As shown and described in the application referred to, the collar has an outwardly projecting portion intermediate its ends which makes the frictional contact with the container body; and the container body has an inwardly projecting bead which contacts with the lower edge of the collar.

An object of the present invention is to provide a container with an inserted collar having an outwardly projecting portion intermediate the upper and lower edges thereof for frictionally gripping the inner wall of the container body, which collar is so constructed that it is not necessary to provide any inwardly projecting bead in the wall of the container body, thus leaving the outer face of the container body smooth and free for decorating.

In the drawing,

Figure 1 is a view partly in side elevation and partly in section showing a container embodying the improvements.

Figure 2 is a vertical sectional view on a larger scale showing the container body and collar separated prior to the inserting of the collar in the container body.

Figure 3 is a similar view showing the parts assembled and the closing end attached to the container body.

The invention has to do with a container which is made easy to open by a tearing strip formed by scoring the metal of the body wall adjacent one end of the container. Within the container is a collar which is located in the region of the tearing strip, which collar is a permanent part of the container body and after the tearing strip is removed serves as a part of the container body to receive the cover for reclosing purposes. The invention has particularly to do with the construction of the collar.

The collar is formed of considerably less diameter than the container body so that it may be easily inserted therein either before or after the container body is flanged. The collar may be formed by drawing the metal of a blank so as to produce a seamless collar, or it may be formed from a strip, the ends of which are joined to

form a cylindrical collar. At its upper edge the collar is rolled inwardly into a hollow bead for concealing the raw edge of the metal and for strengthening and rounding out the collar. Intermediate the upper and lower edges of the collar an outwardly projecting flattened bead is formed in the collar preferably by the use of dies so as to provide an outwardly projecting portion of uniform diameter which contacts with the body of the container for holding the collar in place. This outwardly projecting portion is of slightly larger diameter than the interior diameter of the container body and the collar is forced into the container body, thus making a tight frictional gripping contact therewith. This frictional gripping contact is the sole means for holding the collar in place in the container body. At the lower edge the collar is bent outwardly and upwardly and dimensioned so that the edge of the outwardly and upwardly turned portion will contact with the body wall and thus close the space between the lower portion of the collar and the container body. No bead in the wall of the container body is necessary for the lower edge of the collar to contact with the container body as shown and described in my prior application. The wall of the container is free from beads and is smooth so that it can be readily decorated.

Referring more in detail to the drawing, the container body is indicated at 1 and is of the usual construction. It is preferably cylindrical in shape and is provided with a side seam which may be a lap seam or a lock and lap seam. The container body is provided with a flange 2, as shown in the drawing, which flange is used for the securing of the closing end to the container body. The wall of the container body is scored along the lines 3 and 4 which form a tearing strip 5 having a tongue to which a key may be attached for tearing away said strip to release the end from the container body and thus open the container.

The container body is of uniform diameter all the way between the two flanges to which the ends are attached, and therefore the outer face of the container body may be decorated. When it is necessary to provide the container body with an inwardly or outwardly projecting bead, it greatly interferes with the decorated matter on the outer face of the can.

The invention has to do particularly with a collar which may be inserted in a container and permanently held in place therein without the use of solder or without welding, and particularly

without the use of any bead in the body wall either to hold the collar in place or to prevent movement of the container body. The collar is indicated at 6 in the drawing. The collar, as noted above, may be formed by drawing the metal of a blank so as to produce a seamless collar or it may be formed from a strip, the ends of which are joined to form the cylindrical collar. The invention has to do with the particular shape of the collar rather than the manner of forming the collar. The collar intermediate its end portions is provided with an outwardly projecting flattened bead 7, the outer face of which is of uniform diameter and of a diameter slightly greater than the inner diameter of the container body. The collar at the upper edge is rolled or curled inwardly as indicated at 8. This forms a strengthening bead which maintains the collar in its cylindrical form during the handling of the same and which also conceals the raw edge of the metal, providing a smooth edge at the entrance mouth of the container when it is open. The lower edge of the collar is bent outwardly and upwardly as indicated at 9. This edge portion is so dimensioned that the extreme diameter of the upwardly turned portion is slightly greater than the inner diameter of the container body. The collar 6 described is inserted in the container body after it has been completed and may be inserted after the container body is flanged or prior to the flanging thereof. The inclined outer face of the upturned portion 9 will direct the collar into the container. This upturned portion contacting with the wall of the container will be compressed and bent inwardly and will maintain a firm contact with the inner face of the container. The portion 7 is so dimensioned, as noted above, that it also makes contact with the inner wall of the container body. The portion of the collar leading to the extreme outer diameter of this bead 7 inclines outwardly and further aids in the inserting of the collar into the container body.

The collar expands the container body slightly so that both the upturned lower edge portion and the bead 7 make a very firm frictional gripping contact with the wall of the container body and this will hold the collar in a permanent set position. The collar may be inserted at the same time that the container body is flanged and placed at a definite position relative to the formed flange. It may be partially inserted and finally seated or placed when the cover is pressed into the container body and joined thereto by double seaming.

The cover or closing end is indicated at 10 and the

double seam for joining the end to the container body is indicated at 11. This portion of the container which has just been described is made by the manufacturer, and the container is then shipped to the packer and after the container is filled the end 12 is attached and double seamed to the container body. After the tearing strip is removed the end 10 becomes the cover and, as shown in the drawing, is provided with a depressed portion 13 which slips down outside of the collar just above the bead 7. In other words, the collar proper is spaced away from the wall of the container body a distance which permits this depression in the collar which slips into the container body to pass along the outside of the collar. While I have shown a collar as inset from the body wall and provided with an outwardly projecting portion, it will be understood that from certain aspects of the invention the collar may be made to fit the inner wall of the container all the way from the upper edge thereof to a point adjacent the lower edge and then the lower edge bent inwardly and outwardly to provide an upturned member similar to the member 9 which grips the wall of the container and thus makes unnecessary any inwardly projecting bead.

It is obvious that the invention is not limited to the form of construction shown, but that it may be modified in many ways without departing from the scope of the appended claim.

Having thus described the invention, what I claim as new and desire to secure by Letters Patent, is:

A container comprising a body portion and closure ends seamed thereto, one of which has a depending portion, said body portion being of uniform diameter throughout and having score lines forming a tearing strip, a collar within said container in the region of said tearing strip, said collar having an upper portion offset from the body of the container and forming a recess adapted to receive the depending portion on the closure end, said collar having the lower portion thereof inset from the body of the container and having its lower edge portion rolled outwardly into firm gripping contact with the body of the container for concealing the raw edge of the metal and for holding the collar in the container, said collar having an intermediate portion between said offset portions of slightly larger diameter than the inner diameter of the container whereby when said collar is forced into the container said intermediate portion will firmly grip and serve as a means for securing the collar to the container.
